[57] CLAIM

The ornamental design for a portable capacitive discharge blasting unit, as shown and described.

DESCRIPTION

FIG. 1 is a front elevational view of a portable capacitive blasting unit in accordance with the present design; FIG. 2 is a bottom plan view of said portable capacitive discharge blasting unit;

FIG. 3 is a rear elevational view of said portable capacitive discharge blasting unit;

FIG. 4 is a top plan view of said portable capacitive discharge blasting unit;

FIG. 5 is a right side elevational view of said portable capacitive discharge blasting unit;

FIG. 6 is a left side elevational view of said portable capacitive discharge blasting unit; and,

FIG. 7 is a perspective view of said portable capacitive discharge blasting unit.
